UNITED STATES PATENT OFFICE.

WILLIAM KENT KISE, OF WICHITA, KANSAS.

GAS-MACHINE.

1,369,247.

Specification of Letters Patent. Patented Feb. 22, 1921.

Application filed December 2, 1919. Serial No. 341,929.

To all whom it may concern:

Be it known that I, WILLIAM KENT KISE, a citizen of the United States, residing at Wichita, in the county of Sedgwick and 5 State of Kansas, have invented a new and useful Gas-Machine, of which the following is a specification.

This invention relates to gas machines or means for producing gas from kerosene or 10 coal oil, or the like, in combination with a burner, which by means of the gas so generated, will serve or operate to generate additional gas for use as desired.

A further object of the invention is to provide an improved burner having novel means 15 for heating the coal oil or kerosene as the same is supplied under pressure to the burner, which is adapted for use in connection with stoves, furnaces or other heat generating units, the advantage in using coal oil or kerosene being due to the large number 20 of heat units produced thereby for a given quantity the same as compared with a corresponding quantity of other fuel, such as gasoline, natural gas or coal.

A further object of the invention is to provide a burner which is constructed with a view to simplicity and durability, and in which all of the parts including the burner 25 and generating means are readily accessible for cleaning or repair, and in which the parts of the burner will be very unlikely to clog up.

A further object of the invention is to provide an improved gas generating means and 30 burner adapted for use especially in conjunction with a coal range so as to effectively heat the oven thereof in addition to supplying heat through the openings in the top of 35 the stove, the number of the burners being varied as desired in accordance with the invention.

With the above and other objects in view which will appear as the description proceeds, the invention resides in the combination and arrangement of parts and in the details of construction hereinafter described and claimed, it being understood that, within the scope of what is claimed, changes in 45 the precise embodiment of the invention shown can be made without departing from the spirit of the invention.

In the accompanying drawings:

Figure 1 is a top plan view of a gas machine constructed in accordance with the invention; 50

Fig. 2 is a horizontal longitudinal sectional view taken on line 2—2 of Fig. 3;

Fig. 3 is a vertical longitudinal sectional view of the device; 60

Fig. 4 is a side elevation thereof; and

Fig. 5 is a vertical transverse sectional view taken on the line 5—5 of Fig. 4.

Referring to the drawings in detail, my improved gas machine is preferably made 65 in a form of a casting 10 comprising substantially circular burners 11 and 12 of hollow rectangular cross section as is clearly shown in Fig. 5 of the drawings, although it is to be understood that the same may be 70 of any other suitable design or cross section, so long as the same is hollow and produces a channel or conduit 13 connected by intermediate portions 14 thus forming a substantially elongated loop forming spaced burners 75 placed in communication with the source of gas supply as will be later described. These burners are provided with a series of circular openings 15 having perforated lava burner disks 16 secured thereto. These lava 80 burner disks 16 may be substituted by other suitable burners but are preferred by reason of the produced color in conjunction with the blue green flame of the gas, and radiating a glowing red heat, producing a very 85 desirable appearance, besides the fact that the disks will not corrode and are used for pre-heating or super-heating the gas after the kerosene has been heated to generate the 90 gas, as will be further explained.

Extending longitudinally between and beneath the channels 13 and preferably in parallel relation with respect thereto from one end of the casting is a passageway 17 which terminates at the inner end of the burner 12 95 and is provided with oppositely branching passages 18 communicating through the openings 19 with the burner pipe or channel 13 at either side. The pipe 17 is formed at the top within the burner and between the 100 burners 11 and 12, with pans or cups 20 and 21, the latter of which is formed at the continuation of the passageway 17 beyond the inner end thereof and relatively deep compared to the pan 20, which latter is provided 105 with an upstanding flange 22 designed to divide the same into sections one of which has suitable openings in the bottom thereof opening into the passage 17 and above which are lava disks 23 of the same type as used 110 in connection with the burners 11 and 12 but preferably smaller. The other section

of the pan 20 is designed to contain asbestos or similar absorbing material as indicated at 24, the portion 21 being deeper than the portion 20 and being designed to receive 5 alcohol or the like for initially starting the machine as will also be further explained.

The opposite end of the casting is formed with a vertical air inlet passage or duct 25 which extends downwardly a considerable 10 distance and is open at its lower end, while the wall of the passage 17 extends therethrough horizontally to provide side passages 26, the wall 17 serving as a baffle wall to divide the air rising in the intake pipe 25, 15 whereby the same will be discharged at either side of the mixing chamber 27. The mixing chamber 27 is closed at its upper end, the top of the casting being provided with an opening 28 through which the parts 20 confined therein are readily accessible for cleaning and repair. The opening 28 is closed by a plate 29 so as to cover the mixing chamber when the device is in use and operating. By means of the openings 19, the burners 25 are placed into communication with the supply pipe 17, so that a uniform distribution is insured, the side walls 30 closing the passage 31 which is disposed in communication with the mixing chamber 27 and the passage 30 17 outwardly of the Bunsen tube 32 which is positioned in a passageway between the mixing chamber and the passage 31 and serves as means of siphoning into the latter passage, the proper amount of air to produce 35 a gas which when burned will produce a perfect blue flame and show perfect combustion. The Bunsen tube further operates to maintain the proper and even pressure at all the burner disks. Plugs 33 may be provided in 40 the ends of the passages 17 and 31, in order to obtain access to the interior thereof for cleaning purposes, and the lower portion of the passage 31 produces a pocket designed to receive any accumulation of oil which 45 may be drained by means of a pet cock 34.

The transverse wall of the burner 11 and the innermost transverse wall of the burner 12, are slotted as shown at 35 so as to receive a generating supply tube 36 having connection at one end as shown at 37 for a suitable 50 source of supply for coal oil under pressure, the supply of which is regulated in a suitable manner as by means of a needle valve 38 coöperating with a suitable seat in the end of the tube 36. The tube rests upon a bridge wall 39 at the adjacent end of the casting and extends through an opening in a wall 40 at the inner end of a mixing chamber 27, the axis thereof being on a line with 55 the axis of the tube 32 so that the blast of oil and gas generated in the tube by heating of the latter from the fuel or alcohol in the pan 21 or the pan 22 used to initially cause the generation of the gas therein, is caused 60 to discharge axially into the tube and the

gas generated in the supply passage 17 and is ignited as it passes through the burners 23, it being understood that the pan 21 and burners 23, are extended longitudinally of the device beneath the generating tube 36 as 70 is clearly shown in the drawings. The advantage is that after once lighting the alcohol in the priming pan, this flame will ignite the gas which is generated in tube 36, there being enough oil in tube 36 always to generate gas before it is necessary to open the fuel valve. This insures that the operator will know when generation has taken place and will not make the mistake of opening the fuel valve too soon, as could happen if 80 the alcohol flame were not adjacent to the generating disks 23 which receive the first gas generated.

The device is adapted to be suitably supported for use within a stove, or the like, the 85 shape thereof varying in accordance with the heating unit to which the device is applied. However, in the drawings, the device is constructed especially for fitting a fire box of a range and the burners 11 and 12 are positioned beneath the stove openings and suitable brackets 41 are provided for supporting the device upon the grate, with the lower end of the air inlet passage 25 located in spaced relation thereto to permit the entrance of air which as it mixes with the gas, as described under pressure in the tube 32 flows then through the passage 17, and Bunsen tube 32 described in the manner aforesaid for use for cooking or heating purposes.

The brackets 41 are shown supporting a rectilinear burner 42, at the bottom portion of one side thereof in a horizontal position, the same having the burner disks 43, so as 105 to provide the necessary heat at one side of the fire box, for heating the oven if desired. The gas is supplied to this burner through the medium of an elbow or laterally extended pipe 44, in which is provided a suitable valve 110 45, preferably of the butterfly type adapted to be suitably manipulated for regulating the flow of gas to the burner or entirely cutting off the same as desired. By this means the burners 11 and 12 can be used independently 115 of the burner 42 and the supports or brackets 41 may be removed entirely in case of not desiring to use the burner 42, so that brackets can be secured to both sides of the burners for supporting the device in position.

By supporting the fuel pipe 36 in the manner described, in connection with a transverse bridge wall or partitions 46, it is prevented from bending and getting out of alignment, so that gas and air will not be 125 discharged therefrom except axially into the tube 32. By having the burner 11 slotted as shown at 39, the tube can be inserted into opening 40, and then lowered into the slot at 39 so that the tube may be very 130

readily supported or placed in position, or removed for the purpose of cleaning. Should the gas be disposed out of alinement with respect to the axis of the tube 32, the result 5 would be a less sufficient gaseous product which would produce a yellow flame without proper combustion and would result in a deposit of carbon or lampblack upon the utensils. A cylinder or pencil of carbon- 10 rundum or a copper or steel rod covered with mineral wool or asbestos may be inserted into tube 36 so that the oil will be absorbed and when generation takes place the impurities will be retained in the material. 15 This inserted filler 36' may be removed when it becomes filled with impurities and a new one put in its place. The device will be found efficient and can be economically operated. It is also obvious that any number 20 of burners may be connected, the same being independently controlled. Also, attention is called to the method of dividing the top of the burner and the mixing chamber and the air, the air supplied through the 25 intake being divided at either side of the fuel supply, so as to produce a more thorough mixture. Also, by providing the burners at either side of the device, there is the advantage that one half of the burner 30 may be used in case the other half should become obstructed for any reason not so far apparent as the result of considerable use and experiment. Also attention is called to the construction whereby the very first gas 35 that is generated, passes directly through the Bunsen tube 32 thence to 31, then chamber 17 which furnishes gas to disks 23 which maintains the generation of tube 36 which was originally started by the alcohol in pans 40 20 and 21. Thus, it will be seen that as the gas is generated in tube 36, it leaves the tube orifice in a form of a spray or hot gas which shoots, with force through the mixing chamber 27 and directly into the Bunsen 45 tube 32, the force of the spray siphons in air in the proper amount into the Bunsen tube 32, so that the air will be properly proportioned with the gas and spaced from the gas orifice so that the resultant mixture 50 will when burned produce a perfect blue flame without the usual deposit of carbon, owing to the perfect combustion which results. The only outlet for the Bunsen tube is into the chamber 31 which leads downwardly into the supply 17, thus insuring that the burners 23 will be ignited before it is necessary to supply gas to the burners 11 and 12 thus permitting the machine to operate more quickly and from the gas generated, by the initial heating, from the oil 55 remaining within the tube 36, caused by the heat from the pans 20 and 21, which as understood, have been supplied with alcohol for this purpose. This will result in a quick 60 generation of gas since the burners and initial heating means are adjacent to the burners 11 and 12. It is to be understood that the burners 23 are first ignited, and afterward, the burners 11 and 12. This is accomplished by the small amount of oil 70 that remains in the tube 36 from the time it was used previously, so that the operator observing the gas lighting at the burners 11 and 12, knows that generation has been taking place and that the fuel valve should be 75 opened. This obviates the objection to other machines that generate gas from oil in that it is necessary for them to allow the alcohol to burn a certain length of time and when they think generation has taken place, they 80 open the fuel valve. However, it often happens that the valve is opened too soon, and since no means is provided of knowing when generation has taken place, the result is that oil is discharged into the generating 85 tube before it is hot enough to gasify the oil, so that the oil is caused to be discharged into the burners. This mistake cannot happen with the present device, because the gas which escapes from the burners 11 and 12 90 will be automatically ignited before the supply valve is opened, owing to the disks 16 being adjacent to the pans and burner disks 23.

Having thus described the invention what 95 I claim is:

1. In a gas machine and burner, a casting including spaced burners, said casting having slotted portions, a valved supply pipe supported in said slotted portions, a 100 mixing chamber within one of said burners and having means of access thereto, said mixing chamber having an air inlet at the bottom and receiving said pipe therein, a tube extending through one wall of the mixing chamber in axial alinement with the pipe, a supply pipe leading therefrom beyond said burner tube and communicating with said burners at opposite sides, and means for supporting said casting. 110
2. In a gas machine and burner, a casting including spaced burners, said casting having slotted portions, a valved supply pipe supported in said slotted portions, a mixing 115 chamber within one of said burners and having means of access thereto, said mixing chamber having an air inlet at the bottom and receiving said pipe therein, a tube extending through one wall of the mixing chamber in axial alinement with the pipe, a supply pipe leading therefrom beyond said burner tube and communicating with said burners at opposite sides, a pan having a channel in its upper portion adapted to receive alcohol or the like for initially heating 120 said supply tube, burners in said pan and receiving a supply of gas therefrom, said pan being positioned beneath said tube a pocket formed between the mixing chamber and said pan and having means of draining 130

the same, and means for supporting the device in position.

3. A machine of the class described comprising a substantially elongated casting in 5 a form of a loop of tubular cross section, provided with spaced burners having opposed communicating portions, the opposed sides of said burners being divided to provide slots having recessed bridge walls, the 10 opposed sides of said burners being placed in communication at one end thereof, openings in the central portion of the casting centrally at one end thereof, a mixing chamber formed within the other end and having 15 a top portion and an air inlet, a supply pipe for kerosene supported in said slots and one wall, said mixing chamber having an opening in one wall receiving said supply pipe and having an opening in its opposite 20 wall axially alined therewith, a pocket outwardly offset in the last named wall and provided with means for obtaining access thereto, a conduit extending from said pocket longitudinally beneath the supply 25 pipe and having means for heating said pipe prior to the generation of gas in the mixing chamber and by means of the gas so generated by the heating thereof, said conduit having a baffle wall providing passages at 30 either side of the outlet end of the supply pipe and an outlet for said conduit for connection with additional burners.

4. A machine of the class described comprising a substantially elongated casting in 35 a form of a loop of tubular cross section,

provided with spaced burners having opposed communicating portions, the opposed sides of said burners being divided to provide slots having recessed bridge walls the opposed sides of said burners being placed 40 in communication at one end thereof, openings in the central portion of the casting centrally at one end thereof, a mixing chamber formed within the other wall and having a top portion and an air inlet, a supply 45 pipe for kerosene supported in said slots and one of the bridge walls, said mixing chamber having an opening in one wall receiving said supply pipe and having an opening in its opposite wall in line therewith, a 50 pocket outwardly offset in the last named wall and provided with means for obtaining access thereto, a conduit extending from said pocket longitudinally beneath the supply pipe and having means for heating said 55 pipe prior to the generation of gas in the mixing chamber and by means of the gas so generated by the heating thereof, a rectilinear burner arranged beneath the aforesaid burner and facing the side thereof, and 60 a valved communication between said conduit and said burner.

In testimony that I claim the foregoing as my own, I have hereto affixed my signature in the presence of two witnesses.

WILLIAM KENT KISE.
